UNITED STATES PATENT OFFICE.

CHARLES F. HARLOW, OF BOSTON, AND WILLIAM P. BARKER, OF ORANGE,
MASSACHUSETTS.

CLUTCH.

SPECIFICATION forming part of Letters Patent No. 227,523, dated May 11, 1880.

Application filed March 29, 1880. (No model.)

To all whom it may concern:

Be it known that we, CHARLES F. HARLOW, of Boston, Massachusetts, and WILLIAM P. BARKER, of Orange, Massachusetts, have 5 jointly invented certain new and useful Improvements in Clutches; and we do hereby declare that the same are fully described in the following specification and illustrated in the accompanying drawings.

10 The object of our improvement is to provide a simple and effective clutch for use in connection with any suitable mechanism where it is desired to communicate motion in one direction only to a shaft or other mechanical 15 device.

Our invention consists in a hollow slotted shaft having a spring-pressed spindle provided with a projecting pin adapted to move longitudinally within the bore and slot of the 20 shaft, in combination with a rotary wheel or sleeve on said shaft, formed with a face-cam or ratchet-teeth, which engage with the pin in order to drive the shaft; also, in the combination with said device, of a cap serving to conceal 25 the slotted end of the shaft, together with the ratchet-spring and pin.

In the drawings, Figure 1 is a plan, partly in section, of apparatus embodying our improvements; Fig. 2, a vertical central section 30 of the same, and Fig. 3 a transverse section on the line X X of Fig. 1.

A is a standard or hanger, forming a suitable bearing, in which the shaft B rotates.

C is a collar secured to the shaft between 35 the bearing and the driving-wheel D.

E is a spindle having a limited longitudinal movement within the hollow end of the shaft, and F a pin secured to said spindle and projecting at one or both ends through slots G 40 in the shaft B.

On the face of the wheel D adjoining the pin F there are formed cams or curved ratchet-teeth H, which engage with the pins F when the wheel is turned forward in the direction of 45 the arrow. The effect of this engagement is to rotate the shaft B, through which the pins F pass, and thereby to drive any mechanism connected therewith.

When the motion is reversed by turning 50 the wheel D backward the shaft B stands still, the sloping cam-faces of the teeth H pressing back the pins F in the slots G against the resistance of a light spiral spring, I, coiled around the spindle E, which spring returns

the pins to their working position at every 55 half-turn of the wheel backward, so that they will engage with the teeth H immediately and automatically when the wheel is again given forward motion.

When it is desired to hold the teeth disengaged the spindle and pins may be moved in the hollow shaft and slots by means of the button K on the end of the spindle, and be slightly rotated until the pins enter lateral recesses of the slots G', so that the spring I 65 cannot return them to engagement with the teeth H of the drive-wheel. While thus disengaged the wheel D may revolve freely in either direction without communicating motion.

A cap, L, is slipped over the hollow end of 70 the shaft and held in position by a set-screw or pin, M, bearing against or entering the shaft. This cap is hollow to permit the rotation of the ratchet-teeth, the movement of the spring, and the reciprocation of the pins F, all 75 which parts it conceals and protects. It has the additional functions of a shoulder for the end of the spring to bear against and a collar to keep the wheel D in position for steady movement on its shaft. 80

We claim as of our invention—

1. The hollow slotted shaft B and the spring-pressed spindle and pin, arranged to move longitudinally therein, in combination with the drive-wheel D, provided with the cam or 85 ratchet teeth H, substantially as set forth.

2. The toothed drive-wheel D H, and the hollow shaft B, formed with a slot, G, and a recess or offset thereof, G', in combination with a spring, a spindle having a projecting 90 pin, and a button or equivalent device by which they may be operated, substantially as set forth.

3. The driving-wheel, the hollow shaft, and the reciprocating spindle and pin, in combination with a sleeve or hollow cap, L, adapted to conceal the locking parts and to form a support for the wheel and spring, substantially as set forth. 95

In testimony that we claim the foregoing 100 we have hereunto set our hands in the presence of the subscribing witnesses.

CHARLES F. HARLOW.
WM. P. BARKER.
